GAME APPARATUS

Robert I. Dorfman, New York, N. Y.

Application March 24, 1943, Serial No. 480,269

1 Claim. (Cl. 273—143)

My invention relates to games, and particularly that type of game which employs a large number of prize indicating indicia.

It is an object of my invention to provide game apparatus compact in structure, and possessing means to display a multitude of game indicia; capable of being played by a large number of persons.

It is a further object of my invention to provide in such game apparatus, rotary means, capable of manual rotation, to carry the multitude of game indicia.

It is a further object of my invention to provide an arrangement of the means which carry game indicia, as to effect the exposure of a multitude of such indicia in the minimum of space.

My invention also has for its objects, such as hereinabove are made to appear, and its nature and its peculiar features and advantages will appear in the course of the description.

My invention is also in the combination and arrangement of parts and details of construction as herein set forth and claimed. Reference is had to the accompanying drawings, part of this specification, to explain my invention, it being however, illustrative of only one of the embodiments which my invention may take.

Fig. 1 is a front elevation of my game, showing the facing, the housing, and rotating drum.

Fig. 2 is a plan section taken through the drum along line 2—2 of Fig. 1.

Fig. 3 is a vertical section taken through the drum on line 3—3 of Fig. 1.

Fig. 4 is a layout of a game indicia strip for the drum, partly open and closed.

Fig. 5 is a layout of two such game indicia strips, as combined on the rotating drum.

Fig. 6 is a layout of a series of strips shown in Fig. 5, showing the manner in which they are placed and affixed on the drum.

Fig. 7 is a layout of the pattern of the housing, in which the drum is mounted.

Fig. 8 is an enlarged view of a vertical section of the drum, showing the arrangement of strips bearing game indicia.

Similar numerals refer to similar parts throughout the several figures.

Referring more particularly to the drawings, the game is provided with a housing 9, comprising a cabinet 10, facing 11, and opening 12 in said facing. Drum 13 is mounted in the cabinet 10, by means of shaft 14, which is mounted in holes, pierced in mountings 16, 17. The surface of the drum is covered with a sheet bearing prize indicia strips 18 shown in Fig. 8, on enlarged scale.

In constructing the game, I prefer to cut the housing out of a single sheet of cardboard 19 as shown in layout of the pattern in Fig. 7. Single lines indicate lines of cut, and double lines, the lines at which folding takes place in shaping the housing. The housing is provided with back 20, sides 21, 22, bottom 23 and top 24. Mounting 17 comprises two parts 16a and 17a; and mounting 17, parts 16b and 17b. Parts 16a and 17a are provided with holes 25, 26, and parts 16b and 17b with similar holes 25, 26. Side 21 has extensions 21a and 21b and side 22, extensions 22a and 22b. Top 24 has an extension 24a and bottom 23 an extension 23a.

15 In assembling the housing 9, bottom 23 and top 24 are bent inwardly along lines *f* and *g*, to form the bottom and top of the housing. Part 16a, being cut along lines *a*, *b*, *c*, is easily bent inwardly along line *e* to meet part 17b, similarly

20 cut and bent. The holes 25, 26 of parts 16a and 17a are made to register to receive shaft 14 which carries drum 13. Part 16b is similarly cut along lines *a'*, *b'*, *c'*, and bent inwardly along lines *e'* to meet part 17b similarly cut and bent, and used

25 to form the other mounting, the holes 25, 26 being made to register to receive shaft 14, which carries drum 13. The drum being thus mounted, sides 21, 21 are bent inwardly along lines *i* and *j* to close the cabinet and keep the shaft confined. Extensions 21a, 21b and 22a, 22b are then bent

30 along lines *k*, *l*, *m*, *n* and are affixed by adhesive or other means along the top and bottom respectively covering the holes out of which mountings 16, and 17 were cut, and serving to keep the cabinet 10, together. Extensions 23a and 24a are then bent along lines *o* and *p* as shown in

35 Fig. 3 and the cabinet 10, is then affixed to the facing 11 by stapling 21, or other suitable means. In Fig. 2, the drum 13 is shown with drum 13, sealed at each end by heads 13b, 13c and provided with holes 13d. The shaft 14 is provided with an enlarged mid-section 14a and narrow ends 14b, 14c, the shoulders of the shaft serving to prevent lateral movement of the drum.

40 The length of the drum is slightly shorter than the opening 12 in the facing 11, and the arrangement of the mountings within the cabinet is such as to allow a portion of the surface of the drum to protrude beyond the opening 12 as shown in Fig. 3.

45 In preparing the strips 18 for carrying the game indicia, I prefer to cut strips of paper of length equal to the length of the drum and of width adequate to permit cutting of the strip as shown in Fig. 4. Single lines indicate lines of cut and

double lines, lines of folding. Each strip when cut is thus provided with portion *q*, *r* and *s* and extension *t*. The game indicia is imprinted on extensions *t*, which is then bent onto part *q*, thus concealing the indicia. To complete the sealing of indicia, and prevent the impression of the printing from making the indicia known, flaps *r* and *s* are bent over part *t*, as shown in Fig. 4, to produce a completely folded game tongue *v*. The construction of the strip in this manner leaves spaces *w*, which are filled by superimposing two strips 18 of Fig. 4, one upon the other, as shown in Fig. 5, thus filling the spaces *w* and doubling the number of game tongues *v* in each row, before mounting on sheet 28, as hereinafter described.

I prefer to provide in this manner 18 tongues in a row, each tongue being $\frac{3}{8}$ " in width by $\frac{3}{4}$ " in length, although the number and dimensions may be varied as desired.

The first game strip 18, thus completed, is then mounted upon a sheet of paper 28 of width of the drum, and the length sufficient to cover the surface of the drum. The first strip 18 is then sewn onto the sheet 28 by a double row of stitching 29, 30, shown in Fig. 5, which serves to seal flaps *r* and *s* and extension *t*, and at the same time to attach the strip 18 to sheet 28. The next strip 18 is then placed slightly below the first strip and sewn down in similar manner. The process is repeated until the entire sheet 28 is thus covered, and then the assembly is rolled around drum 13 and affixed thereto by adhesive, as shown in Figs. 1, 3 and 8. A single row of stitching may be used instead of a double row, if desired. In the above manner, I have produced in the minimum of space, 1152 game tongues, by the use of 64 rows of strips. The number may be increased or diminished as desired, and the rows of tongues may be varied in color.

The rules of play for the game are simple and may be varied. The player rotates or spins the drum forward by pushing down over the front surface of the drum exposed at opening 12, allowing it to spin until it stops, or he may rotate it to any particular point desired, or if the rows are colored, to the color preferred. He then pulls one of the tongues off the drum. The double row of stitching has the effect of perforating the tongues at the base, permitting ready severance

when pulled. If the game is a game of prize, then some of the tongues will designate prizes, and other will be blank. If the game is of the kind which requires the players to perform various acts designated on the tongues, the player then performs the designated act for the amusement of the players, a prize being awarded for the best performance. In Fig. 4, there is shown upon the tongue *t*, an act to be performed (Sing.), by way of illustration in this type of game. Other variations are possible and these are by way of example.

It is obvious that the game apparatus may be subjected to various changes in construction without departing from the principle of my invention or sacrificing any of its advantages. Such changes are all intended to be within the scope of my invention. Although I have explained my invention with a certain degree of particularity, it is understood that my present disclosure has been made only by way of example.

Having thus described my invention, I claim:

In a game apparatus, having a housing, comprising a cabinet, a facing for said cabinet, a portion of said facing being cut out to provide an opening for said cabinet; a rotatable drum in said housing; means for mounting said rotatable drum in said cabinet; said rotatable drum being adapted to rest upon said mounting means within said cabinet, and to be rotated at the will of the player, so as to expose to view, through said cut out portion of the housing, the outer surface of said drum; said outer surface of said drum, comprising a sheet of game indicia strips disposed in succession one behind the other, each of said strips comprising a base portion, and extending integrally therefrom a plurality of protruding game tongues, each of said tongues comprising an extension folded back upon itself to conceal game indicia carried thereon, and side overlapping parts to cover said extension and conceal the impression of said indicia; and stitching means disposed along the length of each strip and positioned to seal the base of said tongues and affix said strips to said sheet, said game tongues being thereby adapted to be easily severed from said strips in the course of play, and to be readily opened for inspection of the game indicia thereon.

ROBERT I. DORFMAN.
